BEAM ATTACHMENT CLAMP

Patrick Friel, Richmond Hill, N. Y.

Application September 22, 1948, Serial No. 50,532

3 Claims. (Cl. 248—228)

1

This invention relates to new and useful improvements in a pipe hanger.

The present invention relates to a pipe hanger characterized by a member for attachment to the bottom flange of an I-beam or the like for serving when thus attached to suspend a hanger for a sprinkler or other water pipe, a gas pipe, an electric cable or an analogous service unit; and, more particularly, the aim is to provide a novel and valuable pipe hanger which may be easily and quickly and securely attached, and which throughout is of exceedingly simple and inexpensive construction.

According to the invention, the new clamp may comprise aside from one or more standard nuts, set-screws or the like, such a small plurality of parts that, in one way of carrying out the invention, thereby to provide a clamp adjustable for nice fit attachment to any one of a number of I-beams differing in regard to bottom flange width, the total number of parts present are merely three in number, while, in another way of carrying out the invention, thereby to provide a clamp designed to be attached to an I-beam of a certain bottom-flange width, there are present only two parts.

In the first-mentioned of said two ways of carrying out the invention, the clamp, incorporating two opposing claws plus a member for spanning the underside of the I-beam's bottom flange transversely thereof, has one of these claws threadedly connected to said spanning member, with the other claw coupled to said member otherwise than by a threaded connection therewith. Here each claw is a bent terminal portion of a short length of standard round rod stock.

In the second-mentioned of said two ways of carrying out the invention, said spanning member integrally carries one of the two opposing claws, with the other claw a bent terminal portion of a short length of standard round rod stock, and with the spanning member merely a squarely cut off length of standard strip stock, variously bent.

In either of the preceding ways of carrying out the invention, a length of standard round rod stock may provide one of said claws and also act as a means for directly suspending the hanger, or an additional element of standard round rod stock may be solely used for such suspension.

It is a further object of this invention to construct a hanger for pipes and the like which includes a one-piece member provided at one end

2

with a bent portion for engaging one side of the bottom flange of the I-beam and provided at its other end with spaced finger portions arranged in a manner to be easily bent about the other side of the bottom flange of the I-beam for completing the attachment of the one-piece member to the I-beam.

Another object of the present invention proposes providing the one-piece member with a U-shaped portion between the spaced finger portions with which the threaded top end of a hanger is threadedly engaged for connecting the hanger with the one-piece member in a manner to have a pipe or the like extend therethrough.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:

Fig. 1 shows in transverse vertical section the lower portion of an I-beam, and illustrates in side elevation, attached to the bottom flange of said beam, a pipe hanger constructed in accordance with the present invention.

Fig. 2 is an end elevational view, looking toward the left in Fig. 1.

Fig. 3 is a vertical section, taken substantially on the line 3—3 of Fig. 2.

Fig. 4 is a view similar to Fig. 1, but illustrating the hanger constructed in accordance with a modification of the invention.

Fig. 5 is a top plan view of the spanning member of the device of Fig. 4.

Fig. 6 is an enlarged vertical sectional view, taken on the line 6—6 of Fig. 4.

Fig. 7 is another view similar to Fig. 1, but illustrating another modification of the present invention.

Fig. 8 is still another view similar to Fig. 1, but illustrating still another modification of the present invention.

Fig. 9 is a still further view similar to Fig. 1, but illustrating still another modification of the present invention.

Fig. 10 is an enlarged detailed view of a portion of Fig. 9 in longitudinal section.

Fig. 11 is a perspective view of the spanning member of the form of the invention shown in Fig. 9 prior to attachment to the lower flange of the I-beam.

Fig. 12 is a partial perspective view of the

spanning member from the end opposite that shown in Fig. 11.

In various of these views an I-beam is shown of a standard familiar cross-section, the central web of which is marked 10 and the bottom flange of which is marked 11.

Referring to Figs. 1-3, the clamp here illustrated comprises a spanning member 14, a claw 15 and an opposing claw 16, these claws for engaging and gripping between them the opposite side portions of the flange 11. The claw 15 is established by a bent terminal portion of a round rod 17 of cold rolled steel or the like and having a thread 17', this thread for matching an internal thread 18 in a recess 19 extending longitudinally axially of the spanning member 14; which latter, of cold rolled steel or the like, is generally cylindrical. The claw 16 is established by a bent terminal portion of a round rod 21, of cold rolled steel or the like; said rod having a thread 22.

The spanning member 14 has, at its end opposite to its end from which the recess 19 is extended, a longitudinally extending recess 23 aligned with the recess 19 and internally threaded for taking a hex-head set-screw 24, the shank of which has a thread matching the thread in the recess 23. The free end of the shank of the set-screw 24 is for engaging the rod 21 at a point above the upper end of its thread 22. For this purpose, the spanning member 14 has, further, a vertical cylindrical hole 25 for receiving the rod 21, this hole extending transverse to the length of the member 14 and with its center-line in the same plane as the center-line of the recess 23.

As an auxiliary to said set-screw 24, a nut 26 is threaded on the rod 21. Thus, the nut may be turned up on the rod, against the underside of the spanning member 14, to draw down the claw 16 tight against its side of the flange 11, and then the set-screw 24 may be tightened to prevent angular displacement of said claw, and at the same time assist in holding the nut in its tightened position.

In applying the clamp just described to the I-beam 10, the rod 17 is spirally adjusted relative to the spanning member 14 until, with the claws in line, the grip gap between them is equal to the width of the flange 11. Next, with the rod 21 temporarily removed, the claw 15 is hooked onto the flange 11, the spanning member 14 is arranged against the underside of said flange and at right angle to the length thereof, then the rod 21 is added, and then, as just above stated, the set-screw 24 is tightened and after that the nut 26 is tightened.

In the clamp of Figs. 1-3, the threaded depending length of the rod 21 is prolonged sufficiently to allow threaded connection therewith of a hanger 27 of any desired type.

Referring to Figs. 4-6, here the spanning member 28 is, as shown best in Fig. 5, made simply as a squarely cut off length of standard strip steel stock, said strip being at one end obliquely bent to provide an upwardly projected claw 29 and at its other end being perpendicularly bent to provide a vertically upstanding lug 30.

The opposing claw 31 is established by a bent terminal portion of a round rod 32 of cold rolled steel or the like; said rod corresponding in all respects to the rod 21 except that the top of the thread 33 of the rod 32 is at a higher point thereon, to allow for the fact that the strip stock of which the spanning member 28 is made is of a thickness less than that of the spanning member

14, and, consequently, to permit a nut 34 on the thread 33 to be tightened up sufficiently to draw the claw 31 down tightly on its side of the flange 11.

5 The portion of the rod 32 below the claw 31 and just above and at the upper end portion of the thread 33 is received in a vertical cylindrical hole 35 through the spanning member 28. The threaded portion of the rod 32 is, as in the case of the rod 21, extended downward to a sufficient extent to allow threaded connection therewith of a suitable hanger, for instance one like the hanger 21.

In applying the clamp just described to the I-beam 10, the rod 32 is removed, or, with said rod retained the nut 34 is run down far enough on the thread 33 to allow considerable elevation of the claw 31. In the first of the two cases just mentioned, the claw 29 is hooked onto the flange 11, the spanning member 28 is arranged against the underside of said flange at right angles to the length thereof, the rod 33 is dropped down through the hole 35 and the claw 31 is properly engaged with the flange 11, the nut 34 is turned up to cause the said claw 31 to grip the flange tightly, and the hanger is then added. Or, if prior to hooking the claw 29 onto the flange 11, the nut 34 was merely run down along the thread 33, it is now only required, after arranging the spanning member against the underside of said flange, to turn up the nut 34 to the extent necessary to cause the claw 31 to grip the flange tightly.

Referring to Fig. 7, here again the spanning member 36 is simply a squarely cut off length of standard steel stock. The claw 37, at one end of the member 36, is like the claw 29; but the opposite end of said member 36 is U-bent as at 38 to provide a leg 39 lying below and parallel with the main straight portion of the member 36.

40 The opposing claw 40 is established by a bent terminal portion of a round rod 41 of cold rolled steel or the like; said rod below its claw extending down through a cylindrical aperture 42 in the member 36 and therebelow having a thread 43 so placed that the portion of said rod carrying the upper portion of said thread passes through an aperture 44 in the leg 39 and aligned with the aperture 42. Below the aperture 44 the threaded portion of the rod 41 is of sufficient length to take a nut 45.

45 In the clamp just described, the manner of application which to the I-beam 10 will be understood from what has previously been said, an additional round rod 46 is provided for suspending a hanger, said rod having a thread along the entire length thereof. Vertically aligned cylindrical holes 47 and 48, for passage therethrough of the rod 46, are in, respectively, the main portion of the spanning member 28 and its leg 39; and nuts 49 and 50 are provided to anchor the rod 46 to the clamp.

50 Referring to Fig. 8, here once more the spanning member 51 is simply a squarely cut off length of standard steel stock. The claw 52, at one end of the member 51, is like the claws 29 and 31; and the other end of the member 51 is U-bent as at 53 to establish a leg 54 parallelly underlying the main portion of said member. In this case, however, the vertical spacing of the leg 54 below the main portion of the spanning member is just sufficient to accommodate a nut 55 while somewhat tightly and hence appreciably frictionally engaging the opposite faces of said 55 nut. This nut is for taking a thread 56 of a

round rod 57, of cold rolled steel or the like, and terminally bent at its upper portion to provide a claw 58. The threaded portion of the rod 57 passes through two vertically extending and aligned cylindrical holes 59 and 60 in, respectively, the spanning member 51 and its leg 54.

The threaded depending length of the rod 57 is prolonged sufficiently to allow threaded connection therewith of a suitable hanger, for instance one like the hanger 21.

In the further modification of the invention shown in Figs. 9 to 12, the pipe hanger is characterized by a spanning member 70 mounted transversely across the bottom face of the lower flange 11 of the I-beam. A rod 71 is depended from one end of the member 70 and a hanger 72 has threaded connection with the lower end of the rod 71.

The spanning member 70 is of one-piece construction and formed of a length of metal bent at one end into a claw portion 73 which extends about one side of the bottom flange 11 of the I-beam. The main body portion 74 of the spanning member 70 extends across the bottom face of the bottom flange 11. At the opposite end of the main body portion 74 of the spanning member 70 there is formed a pair of finger portions 75. Prior to application of the spanning member 70 to the bottom flange 11 of the I-beam, the finger portions 75 extend upwards at right angles to the main body portion 74, as shown in Figs. 11 and 12, to be bent about the opposite side of the bottom flange 11, as shown in Figs. 9 and 10, securely attaching the spanning member 70 to the bottom flange 11 of the I-beam.

A U-shaped portion 76 continues from the end of the main body portion 74 between the finger portions 75 and the top end of the rod 71 is threadedly engaged through aligned holes 11 formed in the arms of the U-shaped portion 76. A lock nut 78 is threadedly engaged on the rod 71 and tightened against the bottom face of the U-shaped portion 76 to securely lock the rod 71 in a desired adjusted position relative to the spanning member 70.

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new, and desire to secure by United States Letters Patent is:

1. An I-beam clamp for use with substantially horizontal flanges having free outer edges, comprising an elongated strip of flat material positioned with one face engaging flat against the bottom face of the beam, an upwardly bent claw at one end of said strip engaged over the free edge of one of said flanges and engaging flatly over the top face of said one flange, said strip having its other end extending beyond the free edge of the other flange and reverted downward and under forming a horizontal leg spaced vertically from the bottom face of said beam, said strip and said leg having vertically aligned apertures adjacent the free edge of said other flange, a rod vertically and slideably extended through said apertures and having its top end bent into a claw engaged about the free edge of said other flange for flat engagement with the top side of said other flange adjacent the outer free edge thereof, means drawing downward on said rod holding said second claw in a position engaged about the free edge of said other flange, said drawing means comprising threads formed on said rod below said leg, and a nut threaded onto said rod, and tightened against the bottom face of the leg tensioning the reverted extension of said resilient strip.

free edge thereof, means drawing downward on said rod holding said second claw in a position engaged about the free edge of said other flange.

2. An I-beam clamp for use with substantially horizontal flanges having free outer edges, comprising an elongated strip of flat resilient material positioned with one face engaging flat against the bottom face of the beam, an upwardly bent claw at one end of said strip engaged over the free edge of one of said flanges and engaging flatly over the top face of said one flange, said strip having its other end extending beyond the free edge of the other flange and reverted downward and under forming a horizontal leg spaced vertically from the bottom face of said beam, said strip and said leg having vertically aligned apertures adjacent the free edge of said other flange, a rod vertically and slideably extended through said apertures and having its top end bent into a claw engaged about the free edge of said other flange for flat engagement with the top side of said other flange adjacent the outer free edge thereof, means drawing downward on said rod holding said second claw in a position engaged about the free edge of said other flange, said drawing means comprising threads formed on said rod below said leg, and a nut threaded onto said rod, and tightened against the bottom face of the leg tensioning the reverted extension of said resilient strip.

3. An I-beam clamp for use with substantially horizontal flanges having free outer edges, comprising an elongated strip of flat resilient material positioned with one face engaging flat against the bottom face of the beam, an upwardly bent claw at one end of said strip engaged over the free edge of one of said flanges and engaging flatly over the top face of said one flange, said strip having its other end extending beyond the free edge of the other flange and reverted downward and under forming a horizontal leg spaced vertically from the bottom face of said beam, said strip and said leg having vertically aligned apertures adjacent the free edge of said other flange, a rod vertically and slideably extended through said apertures and having its top end bent into a claw engaged about the free edge of said other flange for flat engagement with the top side of said other flange adjacent the outer free edge thereof, means drawing downward on said rod holding said second claw in a position engaged about the free edge of said other flange, said drawing means comprising threads formed on said rod below said leg, and a nut threaded onto said rod and tightened against the bottom face of the leg tensioning the reverted extension of said resilient strip, and means for supporting a hanger from said strip spaced outwardly from said drawing means.
